United States Patent Office

Des. 226,722
Patented Apr. 17, 1973

226,722

CASSEROLE COVER

Gregory Mirow, Corning, N.Y., assignor to Corning
Glass Works, Corning, N.Y.

Filed June 14, 1971, Ser. No. 153,152

Term of patent 14 years

Int. Cl. D7—01
U.S. Cl. D44—15 A

Fig. 1

Fig. 2

Fig. 3

FIG. 1 is a top plan view of a casserole cover showing my new design.

FIG. 2 is a front elevational view.

FIG. 3 is a side elevational view.

The characteristic feature of the design resides in the specific ornamentation applied to the top surface of the casserole cover.

I claim:

The ornamental design for a casserole cover, as shown and described.
